UNITED STATES PATENT OFFICE.

ANSON B. WETHERELL, OF PITTSBURGH, PENNSYLVANIA.

RAIL STRUCTURE.

1,161,273.

Specification of Letters Patent. Patented Nov. 23, 1915.

Application filed February 11, 1913. Serial No. 747,750.

To all whom it may concern:

Be it known that I, ANSON B. WETHERELL, a citizen of the United States, residing at Pittsburgh, in the county of Allegheny and State of Pennsylvania, have invented certain new and useful Improvements in Rail Structures, of which the following is a specification.

This invention relates to rail structures for railroad and street railway traction service and other analogous uses, and it has for its primary objects the provision of a rail structure which is simple and inexpensive in construction but which has great strength and lasting wearing qualities and which is easy to assemble and take apart; the provision of a rail structure wherein the use of bolts is dispensed with; the provision of a rail structure which is substantially continuous in character, that is to say at no point is there a complete break in the rail; the provision of a rail structure of the character specified in which the parts of the rail are securely braced against relative lateral and vertical displacement, while at the same time the rail as a whole is sufficiently springy to prevent breakages; and in general the provision of a rail having the characteristics described which permits of the ready change or replacement of sections or parts of the rail.

These together with such other objects as may hereinafter appear I attain by means of a construction various embodiments of which are illustrated in the accompanying drawings, wherein—

Figure 1 is a transverse section through the rail; Figure 2 is a side elevation of the rail shown in Figure 1, drawn on a smaller scale; and Figure 3 is a transverse section showing a modification of the form shown in Figures 1 and 2.

In Fig. 1 I have shown a form of my invention. In this form the rail is comprised of two parts, the web portions 23 and 24 respectively carried by the base and head of the rail being so constructed as to interlock against vertical displacement. This is accomplished by providing the web 23 with a longitudinally extending rib or lug 25 which fits into a correspondingly shaped recess or groove 26 formed in the web 24. The head of the rail is recessed or grooved on either side of the web portion 24 by grooves 27 and 28, the former of which being adapted to receive the edge of the web

portion 23. The base of the rail is grooved adjacent the web 23 as at 29. It will be noted that the groove 27 is wider at the base than at the top. In assembling the parts, the head is held at an angle with respect to the base portion and the end of the web 23 is brought into position in the groove 27, after which the web 24 is swung toward the web 23 until the two abut one another in proper co-operative relation. This action is made possible by the shape of the groove 27. As a means for securely locking the sections of the rail together, I provide a key plate 30 which is provided with a downwardly depending lip or flange 31 which fits into the groove 29 and abuts the bottom portion of the web 24 and rigidly holds the two web portions in proper engagement. The upper surface of the plate 30 adjacent the web 23 is undercut at 32. The key plate is held in position by means of a plate 33, the upper edge of which fits into the groove 28 and the lower portion of which engages the undercut portion 32 of the key plate. It will of course be understood that a plurality of key plates are provided and preferably so arranged that their ends abut. The locking plates 33 are provided at intervals as may be needed. In addition to locking the key plates, they serve to brace the rail and are of particular advantage at curves to support the rail against the lateral thrust of the wheels on the head of the rails.

One of the primary advantages of the structure just described resides in the fact, that I am enabled to use a base portion of relatively soft metal and a head or tread portion of harder metal, thus securing the desired combination of strength and wearing qualities. It will be apparent that as rapidly as worn, the tread portions of the rail can be replaced. It will also be observed that the track is reinforced or bolstered, particularly in the construction illustrated in Figures 1 and 2.

Referring now to Fig. 3 it will be seen that I have shown a rail structure substantially like that illustrated in Figures 1 and 2. In this form, however, the locking plate 33 is of larger dimensions and is provided at the top with a nose or rib 33a which projects within the groove 28, the adjacent portions of the plate abutting against the head of the rail and serving to brace it against lateral thrusts. The base of the plate is similarly extended whereby a rigid support

is provided for the rail. In this construction the plate 30 is of spring metal and is bolted to the metal bed plate 34 which rests upon a tie in the usual manner.

5 Having thus described my invention and illustrated its use, what I claim as new and desire to secure by Letters Patent is as follows:—

10 A rail structure comprising in combination a head and a base portion, a web portion on the head, a web portion on the base, means whereby said web portions interlock against relative vertical and lateral displacement when placed in position, and a

key member including a locking member 15 for holding the parts in interlocked position, the key member and head and base portions having interengaging means whereby the key member is locked on movement of the locking member longitudinally 20 of the rail to operative position.

In testimony whereof I have hereunto signed my name in the presence of the two subscribed witnesses.

ANSON B. WETHERELL.
